UNITED STATES PATENT OFFICE.

FRANZ A. HINSKY, OF HOBOKEN, NEW JERSEY.

CUSPIDOR.

SPECIFICATION forming part of Letters Patent No. 761,227, dated May 31, 1904.

Application filed August 29, 1903. Serial No. 171,301. (No model.)

To all whom it may concern:

Be it known that I, FRANZ A. HINSKY, a citizen of the United States, residing at Hoboken, in the county of Hudson and State of New Jersey, have invented certain new and useful Improvements in Cuspidors, of which the following is a specification, such as will enable those skilled in the art to which it appertains to make and use the same.

10 This invention relates to cuspidors; and the object thereof is to provide a device of this class which comprises a main outer or base portion and a supplemental portion adapted to be set therein and removed therefrom and 15 which is designed to be removed and destroyed whenever it is desired to clean the cuspidor.

The invention is fully disclosed in the following specification, of which the accompanying drawings form a part, in which the separate parts of my improvement are designated by suitable reference characters in each of the views, and in which—

Figure 1 is a side view of my improved cuspidor, and Fig. 2 a central vertical section 25 thereof.

In the practice of my invention I provide a cuspidor which is composed of two parts—an outer or base portion *a*, which is bowl-shaped in form, and an inner removable and 30 destructible portion *b*, which is set thereinto when in use, as shown in Fig. 2. The part *a* is composed of wood, metal, or any other suitable material, and the part *b* comprises two separate members *b*² and *b*³, each of which 35 is hollow and conical in form, and said members are secured together at *d* in any suitable or desirable way. The member *b*² of the part *b* is closed at the bottom and provided with a pin *c*, which fits in a corresponding 40 recess *d* in the bottom of the part *a*, and in the form of construction shown the bottom portion of the member *b*² consists of a dish-shaped piece *e*, which is secured in said member *b*² and which is preferably composed of 45 metal and to which the pin *c* is secured or with which said pin is connected. The apex of the member *b*³, which is directed downwardly, is cut away to form an opening *f*, and when the members *b*² and *b*³ are secured to-

gether in the position shown a chamber *g* is 50 formed in the bottom of the member *b*², into which the apex of the member *b*³ projects. The top portion of the member *b*² fits within the top portion of the part *a* of the base portion of the cuspidor, while the top portion of 55 the member *b*³ projects so as to form a rim or flange *i*. Both members or portions of the part *b*, including members *b*² and *b*³, are preferably composed of paper so treated as to be 60 impervious to moisture; but any suitable cheap and destructible material may be employed in the construction of these parts or members.

It will be understood that part *b*, including the members *b*² and *b*³, which are secured together, may be removed from the base portion *a* whenever desired, and the device is used in the usual manner; and whenever it becomes necessary to empty the cuspidor or clean it the part *b* is taken out and destroyed 70 or thrown away, and a new and similar part is placed in the base portion *a*, and the cuspidor is again ready for use.

The pin *c*, which is secured to the member *b*² of the part *b*, holds the part *b* in proper position within the base portion and prevents it sliding or moving laterally therein, and if by accident the cuspidor should be upset and the part *b* become detached the contents of 75 the chamber *g* would remain therein, the position of the member *b*³ and the form thereof serving to close said chamber and to prevent 80 the contents from being spilled out.

The bottom of the member *b*² may be formed in any desired manner, all that is necessary 85 being to secure thereto or connect therewith the pin *c*; but I prefer to use the plate *e* of material which would not be affected if a lighted match should be dropped into the cuspidor.

Having fully described my invention, what I claim as new, and desire to secure by Letters Patent, is—

A cuspidor, comprising a base or bottom part, and a removable part set thereinto and 95 composed of destructible material and consisting of two inverted conical members and one of which is set into the other and secured

thereto, the apex of the inner conical member being smaller than the apex of the outer conical member whereby the shape of said member forms a chamber in the bottom portion of the outer conical member, the apex of the inner conical member being opened and the apex of the outer conical member being closed and provided with an attaching device whereby it is detachably connected with the bottom of the bowl-shaped base, the inner conical member being also provided with a

base, flange or rim, substantially as shown and described.

In testimony that I claim the foregoing as my invention I have signed my name, in presence of the subscribing witnesses, this 17th day of August, 1903.

FRANZ A. HINSKY.
